UNITED STATES PATENT OFFICE.

GILLES HOLST, OF EINDHOVEN, NETHERLANDS, ASSIGNOR TO GENERAL ELECTRIC COMPANY, A CORPORATION OF NEW YORK.

INCANDESCENT ELECTRIC LAMP.

Application filed March 11, 1927, Serial No. 174,626, and in the Netherlands April 10, 1926.

The invention relates to incandescent electric lamps, and more particularly to incandescent lamps in which the absorption of light is reduced by means of a substance usually called a "getter", which has the property of transforming the tungsten vaporized from the filament into a material which absorbs less light. Many chemical substances, such as sodium chloride, cryolite, 10 potassium thallo chloride and calcium fluoride, have been used as getters. A getter such as calcium fluoride may be applied to the filament, for example, by spraying or dipping before the stem is sealed into the 15 bulb of the incandescent lamp. After the lamp is sealed in and exhausted, the filament is heated and the getter evaporates from the filament and precipitates on the inside of the lamp bulb as a transparent or translucent 20 cent layer. Other getters, such as potassium thallo-chloride, may be applied at a certain spot inside the incandescent lamp where the temperature is high enough to cause the getter to dissociate slightly, giving off chlorine, which combines with the 25 vaporized tungsten to transform it into a transparent salt.

One object of this invention is to make incandescent electric lamps and similar devices to be made in such a way that the activity of the getter can be regulated exactly in accordance with the amount of tungsten which evaporates during each unit of time at the filament temperature at which 35 the lamp is designed to operate.

According to the invention the incandescent electric lamp or similar device is provided with an auxiliary electrode carrying a getter which becomes active, as by generating gas, under the influence of an electrical discharge between the auxiliary electrode and the filament, and while active causes the formation with the evaporated material of the filament of transparent chemical combinations or compounds.

When the incandescent lamp is lighted, there will generally be parts of the filament which have a negative potential with respect to the auxiliary electrode, and consequently a discharge of electrons will flow from these parts of the filament, so that the auxiliary electrode will be hit by electrons emitted by these parts of the filament. Under the influence of this electron bombardment the getter on or associated with the

auxiliary electrode will be activated, as, for example, by being dissociated, thereby generating a gas which forms with the evaporated tungsten transparent or translucent chemical compounds, and thereby counteracts the absorption of light which would occur if the vaporized tungsten deposited unchanged on the walls of the bulb.

Preferably, the auxiliary electrode is connected conductively to one of the terminals of the filament, either directly or through a resistance, and is so located with reference to the filament that the total quantity of tungsten which evaporates at normal filament temperature during each unit of time will chemically combine with the gas generated by the getter during the same unit of time. In accordance with a construction which has given very favorable results in practice, a considerable portion of the auxiliary electrode is adjacent a portion of the filament, in some cases surrounding a certain part of the filament like a spiral, and is connected to one of the leading-in wires through a resistance if necessary.

The drawing shows one form of incandescent electric lamp constructed according to the invention. The filament 1 is a coiled tungsten wire connected to the leads or terminals 2 and 3, which are joined to the leading-in wires 4 and 5, hermetically sealed into the press 6 of the stem of the lamp. A part of the filament is adjacent an auxiliary electrode 7, which may be in the shape of a large coil surrounding the filament. The electrode 7 is associated with, and may be covered by a getter, and is connected so as to be of positive potential with reference to the adjacent portion of the filament, as by being conductively connected to the lead 2. If required, a resistor may be inserted in the circuit between the lead 2 and the auxiliary electrode 7, and may be installed in the base of the lamp. By suitably selecting the part of the filament which is adjacent to or is surrounded by the auxiliary electrode 7, the potential difference between this part of the filament and the auxiliary electrode, and consequently the effect of the electron bombardment, and the resultant activity of the getter, may be regulated as desired.

What I claim as new and desire to secure by Letters Patent of the United States, is,—

1. In a device of the character described, the combination of a sealed envelope, lead-

- ing-in wires extending through the walls of said envelope, a filament secured to said lead wires, and an auxiliary electrode connected to act as an anode to a portion of said filament and provided with a material which in response to an electrical discharge to said electrode evolves a gas which forms with the vaporized material of said filament a compound more transparent than said vaporized material.
2. An incandescent lamp comprising a sealed envelope containing a filament and an auxiliary electrode provided with a getter decomposable by an electrical discharge and mounted in such relation to a portion of said filament that at normal operating temperature of said filament an electrical discharge to said auxiliary electrode causes said getter to evolve a chemically active atmosphere at a rate so related to the rate of vaporization of the filament material that all said vaporized filament material is converted by said atmosphere into translucent compounds as fast as it vaporizes.
3. An incandescent lamp having a sealed envelope containing a filament, and an auxiliary electrode coated with a getter rendered active by an electrical discharge to said electrode, said electrode being connected to one terminal of said filament and mounted in

such relation to a part of said filament having a potential differing from that of said terminal that an electrical discharge occurs between said electrode and said part of the filament during operation of the lamp.

35

4. An incandescent lamp having a sealed envelope containing a filament, and an auxiliary electrode coated with a getter rendered active by an electrical discharge to said electrode and connected to one terminal of said filament, said electrode being coiled and surrounding a part of said filament at a potential during operation of the lamp different from the potential of said terminal.

40

5. In a device of the character described, the combination of an evacuated envelope, a filament in said envelope, current supply means for said filament, and an auxiliary electrode which evolves gas in response to an electrical discharge to it and mounted adjacent a portion of said filament, said electrode being connected to said current supply means to be at a potential different from the potential of said adjacent portion of said filament.

45

In witness whereof, I have hereunto set my hand this seventeenth day of February, 1927.
